[57] CLAIM

The ornamental design for a combined base and spout for a sanitary fitting or similar article, substantially as shown and described.

DESCRIPTION

FIG. 1 is a front elevational view of a combined base and spout for a sanitary fitting embodying my new design;

FIG. 2 is a top plan view thereof;

FIG. 3 is a right side elevational view thereof, the left side being a mirror image of the right side shown;

FIG. 4 is a rear elevational view thereof.

The broken line representation of faucet handles in FIGS. 1 through 4 is for purposes of illustration only.

FIG. 1
